UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,193,559.

Specification of Letters Patent.

Patented Aug. 8, 1916.

Application filed May 23, 1914. Serial No. 840,469.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a 20 slug or linotype against the matrices which produce the type characters thereon, and the matrices thereafter returned through distributing mechanism to the magazine from which they started.

25 More particularly, it relates to that form thereof embodying a plurality of magazines, containing matrices of different style or font, and any one of which may be brought into action as desired.

30 In the accompanying drawings, I have shown my invention in preferred form and by way of example, and as applied to the kind of linotype machine generally disclosed in my Letters Patent, No. 1,126,029, dated 35 January 26, 1915, and my previous application for Letters Patent, Serial No. 819,605, filed February 19, 1914; but obviously many changes and variations may be made therein, and in its mode of application, which 40 will still be comprised within its spirit.

Thus, the improvements may be applied to typographical machines of other kinds, such as typesetters and typecasters, or those which handle type or dies, instead of matrices.

45 Generally speaking, I desire it to be understood that I do not limit myself to any specific form or embodiment, except in so far as such limitations are specified in the 50 claims.

Referring to the drawings: Figure 1 is a front elevation, partly broken away, of a portion of a linotype machine embodying my invention; Fig. 2 is a section on the line 55 2—2 of Fig. 1; Fig. 3 is a rear elevation of

the parts shown in Fig. 2; Fig. 4 is a detail of the locking device, etc.; Fig. 5 is a view similar to Fig. 2, but showing the parts in different position; and Fig. 6 is a section on the line 6—6 of Fig. 5.

60

The matrices are stored in the several magazines A, and their release therefrom is effected by the manipulation of the keys A¹, when they are delivered to the assembling mechanism and thence to the casting mechanism, and finally elevated and transferred to the distributing devices. As in my said applications, any selected one of the magazines may be brought into use by the manipulation of a font selecting key B, which 65 through connections B¹ moves the locking devices C of the corresponding magazine to inactive position, so that matrices may pass therefrom into the vertical raceway D³ behind the front plate G². The reverse movement of actuating connections B¹ is effected by springs (not shown herein), so that when a key B is released, the locking device C will be restored to engagement with the escapements. As the keys B are so arranged that the operation of one of them causes the release of a previously operated one, it follows that the selection of a given magazine automatically effects the locking 70 of the escapements of all the other magazines.

75

Each of the magazines A is provided with its own series of escapements E, the latter being engaged by springs (see dotted lines Fig. 2) normally tending to release the extreme matrices. Each series of escapements of the different magazines lying in the same vertical plane is controlled by a single actuating member E³, formed with projections E² located in position to engage beneath the outer end of the several escapements, the member E³ being provided with a spring (see dotted lines Fig. 2) of sufficient strength to overcome the escapement springs and maintain the member E³ normally in 80 its uppermost position. The depression of this member would release all of the escapements, were it not for the fact that all of them except one are held against action by the locking devices C, and accordingly matrices are delivered only from the selected magazine. The member E³ is also formed with a projecting portion E⁵ located in position to engage the lever E⁶, which in turn 85 is connected by a reed E⁷ to the ordinary 90 95 100 105 110

keyboard mechanism, all in the manner well understood in the art, so that the operation of the corresponding key A^1 effects first the depression of the member E^3 and the release 5 of a matrix from the selected magazine, and then frees the member E^3 so that its spring may restore it to its original position.

The machine is provided with a front or frame G pivotally mounted as at G^1 , so that the frame or front, together with the connected parts, may be swung outwardly to give access to the interior when desired. Connected to the frame G , and consequently movable therewith, are the font selecting 10 keys B and their interconnections; the connections B^1 which actuate the stationarily mounted locking devices C ; the front plate G^2 formed with the vertical raceway D^3 ; and the escapement actuating members E^3 , 15 the latter parts being so arranged that when the frame G is moved outwardly, the projections E^2 will be disconnected from the escapements E and the projections E^5 from the operating levers E^6 . The parts so far 20 described, except as hereinbefore indicated, are or may be substantially similar to those illustrated in my said applications, wherein they are designated by substantially the 25 same letters of reference.

In my application No. 819,605, the outward movement of the frame G automatically disconnects the escapement actuating members E^3 from their respective escapements and operating levers, and similarly 30 the inward movement of the frame restores these connections.

It is one of the purposes of my present invention to provide means whereby the outward movement of the frame is prevented 40 until the actuating devices have been disengaged, and whereby their reengagement again locks the frame against movement.

The frame G is provided with the vertically movable bolt K , which in its lowermost position (Figs. 1, 2 and 3) engages 45 with the fixed parts K^1 and holds the frame against movement, and in its uppermost position (Figs. 4 and 5) permits the movement of the frame about its pivot G^1 . The 50 means for operating the bolt K are carried by the frame G and comprise the pivoted lever or handle L , which operates the usual frame locking cam, the connected crank arm L^1 , the link L^2 , the arm L^3 , and the link 55 L^4 connecting the arm to the bolt K . When the lever L is in its lowermost or normal position (Figs. 1, 2 and 3), the bolt K actively engages the fixed part K^1 , and when it is in its uppermost position (Fig. 60 5), the bolt is disengaged therefrom.

The previously mentioned arm L^3 is mounted upon the end of a rocking blade or cam member M , extended transversely across the front of the series of escapement actuating members E^3 , and in position to

engage the projections E^{20} thereon. When the cam or blade M is in its uppermost position (Fig. 2), it is out of engagement with the projections E^{20} , and the members E^3 are permitted to rise so as to bring the projections E^2 into engagement with the escapements E , and the projections E^5 into engagement with the operating levers E^6 . When the cam or blade is in its lowermost position (Fig. 5), it engages the projections E^{20} , and depresses the members E^3 so as to carry the projections E^2 out of engagement with the escapements E , and the projections E^5 out of engagement with the levers E^6 , and this latter position thus permits the free movement of the frame G and the members E^3 into and out of operative relation to the escapements and operating levers.

It will be noted that the blade M and bolt K are both connected to the single operating handle L , so that when the latter is in its lowermost position (Fig. 2), the frame G is locked against movement and the members E^3 are in active relation to 85 their respective operating levers and escapements, and when the handle is in its uppermost position (Fig. 5), the frame G may be freely moved, and the members E^3 are out of active relation to the operating levers and escapements. In other words, the parts are so arranged and related, that the frame may be moved into or out of operative position only when the escapement actuating connection is broken.

As shown in my said application No. 819,605, the font selecting keys B are mounted upon and carried by the frame G , the keys being operable in a vertically slotted plate G^9 and being held in operated position against the force of their connected springs (not shown herein) by the plate G^9 , which is formed with the hooks or detents G^{10} to engage the keys. The plate G^9 is 105 therein controlled by the arm G^{13} pivoted to the frame G , the said arm being provided with a spring G^{14} , which when it is permitted to act shifts the plate G^9 , and thus releases an operated key and insures the locking of the escapements in all the magazines. The arm G^{13} is under the control of 110 the link G^{15} slidably mounted in the frame G , and in the said application the action of the slide or link is controlled by the actuated movement of the frame into and out of 120 operative position.

In the present instance I effect the control of the link or slide G^{15} from the previously mentioned locking bolt K , its lower end being suitably beveled to engage with 125 a projection on the slide, as best shown in Figs. 3, 4 and 6. When the bolt K is in its active or locking position (Figs. 2 and 3), the link G^{15} is held in its extreme right-hand position (Fig. 1) and the arm G^{13} con- 130

sequently holds the locking plate G^9 so as to insure the retention of an operated key B . This is the condition that exists when a magazine has been selected and the various parts 5 are in operative relations. When the bolt K is elevated (Fig. 4), the slide G^{15} is released, and the spring G^{14} and arm G^{13} shifts the plate G^9 to release an operated key B . This is the condition that exists when the 10 frame G is unlocked and the parts are in inoperative relation. It will thus be seen that the frame cannot be moved until the font selecting keys and their connected parts have been restored to their normal position. More 15 specifically, I have provided common means to unlock the frame, to shift the actuating devices out of engagement with their escapements, and to restore the selecting devices to normal position, thereby mechanically minimizing the liability to inconvenience and accident. 20

As previously stated, I have shown my improvements only in preferred form and by way of example, and as applied to linotype machines, but obviously many modifications and alterations therein, and in their mode of application, will suggest themselves to those skilled in the art, without departure from the scope of the invention. 25

30 Having thus described my invention, its construction and mode of operation, what I claim and desire to secure by Letters Patent of the United States, is as follows:

1. In a typographical machine, the combination of a magazine having a series of escapements, a series of actuating devices therefor located in advance of the magazine, a supporting frame for said devices mounted to move outwardly away from the magazine, means for disconnecting the actuating devices from their escapements, and means for preventing the movement of the frame until the actuating devices have been so disconnected. 35

2. In a typographical machine, the combination of a magazine having a series of escapements, a series of actuating devices therefor located in advance of the magazine, a supporting frame for said devices mounted to move outwardly away from the magazine, and means to insure the disconnection of the actuating devices from their escapements before the frame is moved. 40

3. In a typographical machine, the combination of a magazine having a series of escapements, a series of actuating devices therefor located in advance of the magazine, an outwardly movable supporting frame for said devices, means for locking the frame 45 against movement, and mechanism for shifting the actuating devices into and out of operative relation with their escapements as said locking means are rendered active and inactive, respectively. 50

65 4. In a typographical machine, the com-

bination of a magazine having a series of escapements, a series of actuating devices therefor located in advance of the magazine, an outwardly movable supporting frame for said devices, mechanism for shifting said devices out of operative relation with their escapements, and means controlled by said mechanism for locking the frame against movement. 70

5. In a typographical machine, the combination of a series of escapement-actuating devices, a movable supporting frame whereby they are carried bodily to and from operative position, and manually-controlled means carried by the frame for shifting the actuating devices longitudinally from their normal position on the frame. 75

6. In a typographical machine, the combination of a series of escapement-actuating devices, a movable supporting frame whereby they are carried bodily to and from operative position, and means for shifting the actuating devices longitudinally from their normal position on the frame before it is moved from its operative position. 80

7. In a typographical machine, the combination of a series of escapement-actuating devices, a movable supporting frame whereby they are carried bodily to and from operative position, means for locking said frame in its operative position, and mechanism carried by the frame whereby the release of said locking means will shift the actuating devices longitudinally from their normal position on the supporting frame. 90

8. In a typographical machine, the combination of a series of escapement-actuating devices, a movable supporting frame whereby they are carried bodily to and from position, mechanism carried by the frame for shifting the actuating devices to an abnormal position on the frame, and means for preventing the return of the frame to operative position unless the actuating devices are in abnormal position thereon. 105

9. In a typographical machine, the combination of a series of escapement-actuating devices, a movable supporting frame whereby they are carried bodily at will from operative position, and means carried by the frame to maintain the actuating devices in an abnormal position on the frame after it is moved from its operative position. 115

10. In a typographical machine, the combination of a series of escapement-actuating devices, a movable supporting frame whereby they are carried bodily to and from operative position, and means for maintaining the actuating devices in an abnormal position on the frame when it is out of operative position, the said means being releasable when the frame is in its operative position to permit the return of the actuating devices to their normal position thereon. 120

11. In a typographical machine, the com- 125

bination of a series of shiftable font-selecting devices, a movable assembling front or frame, and means to insure the location of said devices in normal position before the 5 frame is moved.

12. In a typographical machine, the combination of a series of shiftable font-selecting devices, means for locking said devices in their shifted position, a movable assembling front or frame, and mechanism to prevent the movement of the frame until said 10 selecting devices have been released.

13. In a typographical machine, the combination of a series of shiftable font-selecting devices, means for locking said devices in their shifted position, a movable assembling front or frame, means for locking said frame against movement, and connections 15 between the two said locking means whereby the unlocking of the frame will effect the 20 unlocking of the selecting devices.

14. In a typographical machine, the combination of a plurality of magazines, escapement mechanism for all the magazines, 25 actuating members connected to the escapement mechanism, locking devices, one for each magazine, to retain the type or matrices therein, a movable supporting frame carrying the escapement actuating members, and 30 mechanism to prevent the movement of the frame unless all the locking devices are in active position.

15. In a typographical machine, the combination of a plurality of magazines, escapement mechanism for all the magazines, 35 actuating members connected to the escapement mechanism, locking devices, one for each magazine, to retain the type or matrices therein, a movable supporting frame carrying 40 the escapement actuating members, locking means for holding the frame in its operative position, and connections whereby the unlocking of the frame effects the locking 45 of the type or matrices in all the magazines.

16. In a typographical machine, the combination of a magazine provided with a locking device for the type or matrices, an operating member for the locking device, a 50 movable supporting frame for said operating member, and means to restore the operating member to its normal position on the frame before the latter is moved from its operative position.

55 17. In a typographical machine, the combination of a magazine provided with a locking device for the type or matrices, an operating member for the locking device, a movable supporting frame for said operating member, and means for preventing the movement 60 of the frame until the operating member is restored to its normal position thereon.

18. In a typographical machine, the combination of a magazine provided with a locking device for the type or matrices, a mov- 65

able supporting frame, a shiftable operating member for the locking device mounted upon said frame, means for locking the operating member in its shifted position, means for locking the frame against movement, and connections between the two said locking means whereby the unlocking of the frame will effect the unlocking of the operating member. 70

19. In a typographical machine, the combination of a plurality of magazines each provided with a series of escapements and with a movable locking device therefor, means for moving one of said locking devices to inactive position independently of the others, a series of actuating devices common to the several series of escapements, a movable supporting frame for the actuating devices, mechanism for shifting the actuating devices out of operative relation to the 75 escapements independently of the movement of the supporting frame, and means whereby the shifting of said actuating devices will restore the said locking device to active position. 80

20. In a typographical machine, the combination of a plurality of magazines each provided with a series of escapements, a series of actuating devices for the escapements, a plurality of shiftable devices for 95 selecting one or another of the magazines for use, and manually operable mechanism for shifting the actuating devices out of engagement with the escapements and simultaneously restoring the selecting devices to 100 their normal position.

21. In a typographical machine, the combination of a plurality of magazines each provided with a series of escapements, a series of actuating devices for the escapements, a movable frame upon which said devices are mounted, locking means to prevent the movement of the frame, a plurality of shiftable devices for selecting one or another of the magazines for use, and common 105 mechanism to unlock the frame, to shift the actuating devices out of operative relation with their escapements, and to restore the selecting devices to their normal position. 110

22. In a typographical machine, the combination of a plurality of magazines each provided with a series of escapements, a single series of actuating devices adapted to actuate all the escapements of the several series simultaneously, means for shifting the actuating devices out of operative relation to the escapements, a movable supporting frame whereon the actuating devices are mounted, and means for preventing the movement of the frame until the actuating devices have been shifted out of operative 120 relation to the escapements. 125

23. In a typographical machine, the combination of the magazines A each provided on its under side with the series of escape- 130

ments E, the actuating devices E³ formed with the projections E² which engage beneath the escapements of the several series, a movable supporting frame for the actuating devices, means for depressing the actuating devices relatively to their supporting frame to disengage the projections E² from the escapements E, and means to prevent the movement of the supporting frame until the 10 actuating devices have been so depressed.

24. In a typographical machine, the combination of a plurality of magazines each provided with a locking device for the type or matrices, a series of operating members 15 connected to the locking devices of the several magazines, a movable supporting frame for the operating members, and means to prevent the movement of the supporting frame unless all the operating members are 20 in normal position.

25. In a typographical machine, the combination of a plurality of magazines each having a series of escapements, a common series of actuating members connected to 25 the escapements of the several magazines, locking devices, one for each magazine, for holding the escapements against action, a movable supporting frame carrying the escapement actuating members, and mechanism 30 to insure the locking of the escapements of all the magazines before the frame is moved.

26. In a typographical machine, the combination of a plurality of magazines each 35 having a series of escapements, a common series of actuating members connected to the escapements of the several magazines, locking devices, one for each magazine, for holding the escapements against action, a movable supporting frame carrying the escapement actuating members, locking means 40 for holding the frame in its operative position, and connections whereby the unlocking of the frame effects the locking of the escapements of all the magazines.

27. In a typographical machine, the combination of a plurality of magazines, escapement mechanism for all the magazines, actuating members connected to the escapement mechanism, locking devices, one for each magazine, to retain the type or matrices 50 therein, means whereby the movement of one of the locking devices to inactive position effects the movement of another to active position, a movable supporting frame carrying the escapement actuating members, and mechanism to prevent the movement of the frame until the inactive locking device has been restored to active position.

28. In a typographical machine, the combination of a plurality of magazines, escapement mechanism for all the magazines, actuating members connected to the escapement mechanism, locking devices, one for 60 each magazine, to retain the type or matrices

therein, means whereby the movement of one of the locking devices to inactive position effects the movement of another to active position, a movable supporting frame carrying the escapement actuating members, locking means for holding the frame in its operative position, and connections whereby the unlocking of the frame restores the inactive locking device to active position. 70

29. In a typographical machine, the combination of a plurality of magazines each provided with a series of escapements, a common series of actuating members connected to the escapements of the several magazines, a movable supporting frame 75 carrying the escapement actuating members, locking means for holding the frame in its operative position, and means whereby the unlocking of the frame effects the shifting of the actuating members thereon out of 80 operative relation to the escapements.

30. In a typographical machine, the combination of a plurality of magazines, escapement mechanism for all the magazines, a single series of actuating members 90 connected to the escapement mechanism, a movable supporting frame carrying the actuating members, and means operable independently of the movement of the supporting frame for disconnecting the actuating members from the escapement mechanism. 95

31. In a typographical machine, the combination of a plurality of magazines, escapement mechanism for all the magazines, a single series of actuating members connected 100 to the escapement mechanism, a movable supporting frame carrying the actuating members, and means for shifting the actuating members relatively to the supporting frame and independently of the movement 105 of the latter to break their operative connection with the escapement mechanism.

32. In a typographical machine, the combination of a plurality of magazines each having a locking device for the type or 110 matrices, escapement mechanism for all the magazines, a single series of actuating members connected to the escapement mechanism, a movable supporting frame carrying the actuating members, means operable independently of the movement of the supporting frame for shifting the actuating members relatively thereto to break their operative connection with the escapement mechanism, and mechanism to insure the locking 115 of the type or matrices in all the magazines when the escapement actuating members are so shifted.

33. In a typographical machine, the combination of a plurality of magazines each 125 having a locking device for the type or matrices, escapement mechanism for all the magazines, a single series of actuating members connected to the escapement mechanism, means whereby the movement of one 130

of the locking devices to inactive position effects the movement of another to active position, a movable supporting frame carrying the escapement actuating members, 5 means operable independently of the movement of the frame for shifting the actuating members relatively thereto to break their operative connection with the escapement mechanism, and mechanism whereby the 10 said shifting of the actuating members restores the inactive locking device to active position.

34. In a typographical machine, the combination of a plurality of magazines, escapement mechanism for all the magazines, actuating members connected to the escapement mechanism, locking devices, one for 15

each magazine, to retain the type or matrices therein, shiftable actuating rods connected to the locking devices, means for holding 20 said actuating rods in their shifted position, a movable supporting frame carrying the escapement actuating members, locking means for holding the supporting frame in its operative position, and connections 25 whereby the unlocking of the frame disengages the holding means for the shiftable actuating rods.

In testimony whereof, I have affixed my signature in presence of two witnesses.

DAVID S. KENNEDY.
